DESIGN FOR CENTER-PIECE.

Design No. **11,233**, dated June 10, 1879

UNITED STATES PATENT OFFICE.

SAMUEL KELLETT, OF SAN FRANCISCO, CALIFORNIA.

DESIGN FOR CENTER-PIECE.

Specification forming part of Design No. **11,233**, dated June 10, 1879; application filed March 6, 1879.
[Term of patent 7 years.]

To all whom it may concern:

Be it known that I, SAMUEL KELLETT, of the city and county of San Francisco, State of California, have invented and produced a new and original Design for a Center-Piece, of which the following is a specification.

The drop or inner part of center-piece is composed of plain leaves inclosed by bead-molding with bands overlying. A grape-vine wreath forms middle part of design. This also is inclosed by bead-moldings banded at intervals. A string of round beads circles molding. A shell, scrolled on inner ends, throws out to right and left stems and clusters of fruit and berries. These figures repeat. Between points of fruit and berries a device with rosette in center throws out stems and

triplet leaves. Plain moldings broken into panels form outside finish of design.

The letter A indicates inner portion of center-piece; B, bead-molding; C, wreath, vine, and grapes; D, bead-molding inclosing same; E, stringing of round beads; F F F, shell, fruit, and berries; G, device with rosette in center, throwing out triplet leaves; H, moldings that form outside finish of design.

What I claim as new, and desire to secure by Letters Patent, is—

The design for center-piece, as shown and described.

SAML. KELLETT.
